UNITED STATES PATENT OFFICE.

FRANCIS W. BELL, OF NUNICA, MICHIGAN.

BURNER FOR STEREOPTICON AND MOTION-PICTURE MACHINES.

1,083,654.

Specification of Letters Patent.

Patented Jan. 6, 1914.

Application filed March 21, 1913. Serial No. 756,050.

To all whom it may concern:

Be it known that I, FRANCIS W. BELL, a citizen of the United States, residing at Nunica, in the county of Ottawa and State 5 of Michigan, have invented certain new and useful Improvements in Burners for Stereopticon and Motion-Picture Machines, of which the following is a full, clear, and exact specification.

10 This invention relates to incandescent burners, of the type disclosed in my application filed November 25, 1912, Serial No. 733,899, especially adapted for projecting stereopticon and motion pictures, and has 15 for its object to provide an economical burner capable of giving a very high candle power light for these purposes.

Another object is to produce a burner having a plurality of incandescent mantles 20 so arranged and overlapped that an unbroken field of light of substantially uniform intensity is produced.

A further object is to produce a burner employing a plurality of incandescent mantles arranged to generally conform to 25 the shape of the picture to be projected.

Still other objects are to attain the maximum intensity in the light projected from 30 a group of incandescent mantles, and to gain all of the foregoing objects in a burner using gas manufactured in its own individual generator, whereby the present improved burner may be employed with equal success in cities and rural districts.

35 The invention will be first hereinafter described in connection with the accompanying drawings, which constitute a part of this specification, and then more particularly pointed out in the claims at the end of the 40 description.

In the drawings, wherein the same reference characters are used to designate similar parts throughout: Figure 1 is a side elevation of a burner constructed in accordance 45 with my invention and applied to the lamp house of a motion picture apparatus, said lamp house and the condensing lenses and reflector therein being shown in section, the generator attached to the lamp house being 50 also shown in side elevation. Fig. 2 is a front elevation of the burner proper, Fig. 3 is a top plan view of the same, and Fig. 4 is a front elevation showing a different arrangement of mantles.

55 As illustrated in the drawings, the burner is adapted to support a central mantle A,

two end mantles B, B, and two intermediate mantles C, C. The central and end mantles are preferably arranged in the same transverse plane or, in other words, are in alignment with one another viewed from either side of the burner. The intermediate mantles are in alignment with each other viewed in the same direction, but are arranged slightly in rear of the other mantles. 60 Said intermediate mantles should be placed not more than one inch behind the front mantles, for otherwise they will impair the uniformity of the light. The rear mantles are also slightly overlapped upon the front 65 mantles so as to leave no break in the field of light, see Fig. 2.

The five mantles are adapted to be supported on one or the other of two tubular transverse members D and E to which gas is 70 supplied by longitudinal pipes F and G, respectively. The lower one, D, of said transverse members, is provided with five upwardly extending branches suitably arranged and spaced to support five mantles 75 in the relative positions already described and as illustrated in Fig. 4. The middle branch d is designed to support the central mantle A, the next branches d', d', on either side, are intended to support the intermediate mantles C, C, while the end branches d², d², may support the end mantles B, B, Fig. 4. 80

It will be seen by reference to Fig. 1 that the branches d', d', are offset rearwardly from the plane of the other branches and the 90 member D, in order to support the intermediate mantles in proper position slightly in rear of the other mantles, as described. All of the five branches of the member D terminate at the same height, but the 95 branches d' and d² are provided with removable tubular extensions d³ and d⁴, respectively, the extensions d⁴ being longer than the extensions d³, see Fig. 2. The upper member E has two branches e arranged 100 above and in alignment with the end branches d² of the lower member.

It is sometimes desirable to have a generally circular or oval field of light radiated by the burner in order to secure uniform intensity over the entire surface of the condensing lens. For this purpose, the burner may be equipped with different sizes of mantles, as illustrated in Figs. 1 and 2. The central mantle in this instance is longer than 105 any of the others, while the intermediate mantles are somewhat shorter and the end 110

mantles shorter still. All the mantles are placed with their transverse median lines in the same horizontal plane, so that the general outline of the entire group is circular or oval. It will be noted that the extensions d^3 are used on the branches d' to support the intermediate mantles. The extensions d^4 are also shown in Fig. 2 as applied to the branches d^2 in position to support the end mantles, if desired, but in this figure said end mantles are shown supported on the branches e of the upper member E, it being optional which of these arrangements is employed. When said end mantles are supported on the branches e , as here shown, the flow of gas is cut off from the branches d^2 by valves d^5 .

If a square or rectangular field of light is preferred, the arrangement illustrated in Fig. 4 may be employed. In this instance, the extensions d^3 and d^4 for the branches d' and d^2 , respectively, of the lower member D, are removed, the pipe F and member E also taken off, and five mantles of uniform length are placed on the five branches of said lower member. The valves d^5 are, of course, opened to supply gas to the end branches d^2 , and the valve h , Fig. 1 closed.

The supply pipes F and G for the upper and lower members D and E, respectively, preferably extend rearwardly beyond the lamp house H and are there connected to a pipe I leading from the generator K. A valve g is placed in the supply pipe G in order to cut off the flow of gas to the lower member D when desired, as when the burner is not in use.

The generator may be rigidly connected to the lamp house by links or connecting bars L to permit the burner to be adjusted longitudinally of said lamp house without disturbing the connection of pipe I with said generator. It will be understood that any suitable generator may be employed which is adapted to make gas from gasoline, alcohol, or other hydrocarbon.

In Fig. 1, M designates the usual condensing lenses, and N a reflector suitably supported in the lamp house behind the burner. The use of the reflector raises to the maximum the intensity of the light projected from the group of mantles, the thin films of the mantles themselves offering practically no obstruction to the passage of the reflected light.

It will be understood that detail changes or alterations may be made in the structures herein shown and described without departing from the spirit or sacrificing the advantages of my invention. For instance, the end mantles may be dispensed with by closing the valves d^5 and h and the burner operated with only the three middle mantles which may be of different sizes, as shown in Fig. 2, or of the same size, as illustrated in

Fig. 4. Moreover, the upper and lower members D and E may be reversed or inverted so that the majority or all of the mantles may be supported by the upper instead of the lower member, if desired.

Having thus described my invention, what I claim as new and desire to secure by Letters Patent of the United States is:

1. The combination with an incandescent burner having a plurality of spaced mantles arranged in a plane transverse to the direction of projection of the light, and a plurality of mantles arranged in a plane parallel to the plane of the first mentioned mantles and each overlapping one of the spaces between said first mentioned mantles, of a projecting lens arranged parallel to the plane of said first mentioned mantles.

2. In an incandescent burner, the combination with a central mantle, of smaller mantles arranged at either side thereof and overlapping said central mantle, and other still smaller mantles arranged at the outer sides of the medium sized mantles and overlapping the same, the medium lines of all of the mantles being arranged in the same horizontal plane.

3. In an incandescent burner, the combination with upper and lower tubular members, each having a plurality of branches extending toward each other, of mantles adapted to overlap one another when mounted on said branches, certain of the branches on the respective members being arranged in vertically aligned pairs, whereby mantles can be operatively carried by only one of each of said pairs of branches at a time, and each branch of each vertically aligned pair being constructed to support a mantle when the other branch of the same pair carries no mantle.

4. The combination with an incandescent burner having two spaced mantles arranged in a plane transverse to the direction of projection of the light, and a mantle arranged out of the plane of the first mentioned mantles and overlapping the space between them, of a reflector arranged behind the mantles and parallel to the plane of said first mentioned mantles.

5. In an incandescent burner, the combination with a tubular member having a plurality of branches extending in the same direction, of mantles adapted to be supported directly on all of said branches with their median lines in the same horizontal plane, and extensions for certain of said branches, said extensions adapted to carry the mantles instead of their respective branches, whereby smaller mantles may be used on said extensions and still have their median line arranged in the same horizontal plane with the median lines of the mantles supported directly on the branches, for producing a substantially circular field of light.

6. In an incandescent burner, upper and lower tubular members arranged in the same vertical plane and having branches extending toward one another and arranged in the same plane with the two members, one of said tubular members also having a branch intermediate of the other branches and projecting out of the vertical plane of said members, and mantles adapted to be supported on the branches to form an overlapping group.
7. In an incandescent burner, upper and lower tubular members arranged in the same vertical plane and having branches extending toward one another and arranged in the same plane with the two members, one of said tubular members also having a branch intermediate of the other branches and projecting out of the vertical plane of said members, and mantles adapted to be supported on the branches to form an overlapping group.
- 5
- 10
- 15
- same plane with the two members, one of said tubular members also having a plurality of branches arranged in a plane parallel to the plane of the other branches and intermediate of said other branches, and 20 mantles adapted to be supported on the branches to form an overlapping group.
- In testimony whereof I have signed my name to this specification in the presence of two attesting witnesses.

FRANCIS W. BELL.
